UNITED STATES PATENT OFFICE.

AUGUST SCHILLMÖLLER, OF SAN FRANCISCO, CALIFORNIA.

BUTTON-FASTENING MACHINE.

SPECIFICATION forming part of Letters Patent No. 392,761, dated November 13, 1888,

Application filed July 21, 1888. Serial No. 280,625. (No model.)

To all whom it may concern:

Be it known that I, AUGUST SCHILLMÖLLER, of San Francisco, in the county of San Francisco and State of California, have invented a new and Improved Button-Fastening Machine, of which the following is a full, clear, and exact description.

The object of the invention is to provide a new and improved machine for fastening buttons on shoes, gaiters, &c.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a side elevation of the improvement. Fig. 2 is a plan view of the same. Fig. 3 is an end elevation of the same in the uppermost position. Fig. 4 is a similar view of the same in its lowermost position. Fig. 5 is a sectional plan view of the button-receptacle on the line $x-x$ of Fig. 1. Fig. 6 is a perspective view of the button and its staple. Fig. 7 is a side elevation of the movable button-holder. Fig. 8 is a cross-section of the same on the line $y-y$ of Fig. 7. Fig. 9 is a side elevation, partly in section, of the anvil. Fig. 10 is a perspective view showing the improvement as applied to a table and operated by a treadle. Figs. 11 and 12 are detail views of the pivoted arms.

The improved button-fastening machine A is provided with the pivoted arms B and B', pivoted together at B², and having their free ends pressed apart by a spring, C, secured by one end to the arm B' and pressing with its other free end against the arm B, as is plainly shown in Fig. 1. The front part, B³, of the arm B' actuates the button-holder D, and the front part of the arm B is forked into the arms B⁴ and B⁵, of which the former carries an anvil, E, and the latter carries at its top the button-receptacle F, consisting of a cylinder mounted to turn in its center on a bolt, G, secured to the arm B⁵. The cylindrical button-receptacle rests at its lower end on a disk, H, also secured to the top of the arm B⁵.

The upper end of the cylindrical button-re-

ceptacle F is closed by a disk, I, held to rotate on the bolt G, and provided with handles I' for turning the said disk I. A nut, G', screws on the upper end of the bolt G against washers formed on the receptacle F and resting on top of the disk I, so as to hold the latter and the said receptacle in place. In the disk I is formed an aperture, I², adapted to register with a series of channels, F', formed vertically in the receptacle F and arranged in a circle on the same. The channels F' are semi-cylindrical, as shown in Fig. 5, and are provided at their ends with double flanges F², from which extend outward the vertical flanges F³, for guiding the staple W' and its offset W², said staple holding the button W. (See Fig. 6.)

The lower end of each channel F' is adapted to register with a downwardly-extending chute or guideway, J, secured to the disk H, leading to the button-holder D, and containing in its lower end a spring, K, for preventing the buttons from moving into the button-holder D. The latter is provided with a longitudinal slot, D', into which projects the outer end of the arm B³. The button-holder D is also provided with the upwardly-extending rod D², mounted to slide vertically in a guideway, L, secured on the outer end of the disk H. In the lower part of the button-holder D is formed a transverse opening, D³, and in the bottom of the said opening is formed a longitudinal slot, D⁴, into which passes the eye of the button W. In the opening D³ is also held a retainer, N, similar in shape to the opening D³ and also having a slotted bottom, N', which registers with the slot D⁴ and through which also passes part of the eye of the button W. The retainer N rests at its bottom on the bottom of the opening D³ of the button-holder D and supports the button W as the same is moved from the chute or guideway J into the opening D³. From the upper end of the retainer N extends upward an arm, N², held to slide in a bearing, D⁵, secured to the button-holder D.

The outer end of the arm N² is connected with a screw, O, secured in the lower end of a rod, O', mounted to slide vertically in lugs L', secured to the guideway L. A spring, O², is coiled on the said rod O', and rests at its lower end on the lowermost lug L' and at its upper

- end against the set-screw O^3 , fastened to the rod O' . The spring O^2 has the tendency to press the rod O' and the retainer N upward when the button-holder D moves downward.
- 5 On the front of the guideway L is held a spring, P , by fastening its upper end against the said guideway by means of a disk, P' , and a set-screw, P^2 , screwing through the said disk into the said guideway L . The end of the 10 spring P is then formed into a coil, P^3 , and continues in the downwardly-extending rod P' , curved inward at its lower end at right angles to and extending across the bottom of the button-holder D . The lower arm, P^5 , is pointed 15 at its outer end and fits into a groove, D^6 , extending vertically on the front of the button-holder D and terminating at its upper end in a downwardly-extending inclined groove, D^7 , which is somewhat deeper than the groove D^6 , 20 so that when the said arm P^5 of the spring P travels upward its pointed end drops into the groove D^7 and at a downward movement of the spring passes along the said inclined groove D^7 until it reaches the lower end of the button- 25 holder D , so as to snap under the said lower end and back into its former position. The spring P , on account of its peculiar fastening and the coil P^3 , has a sidewise swinging motion and also a longitudinal swinging motion.
- 30 The anvil E is provided with two transverse grooves, E' and E^2 , placed opposite each other and adapted to clinch the pointed ends of the staple W' . On the under side of the arm B' , supporting the said anvil E , is secured a spring, 35 Q , extending upward on both sides of the anvil E and held in place by a set-screw, Q' , passing through a slot, Q^2 , in the said spring Q and screwing into the outer end of the arm B' . The ends of the spring Q support the eyes 40 R and R' , through which passes the leather strip S directly over the top of the anvil E and in line with the grooves E' and E^2 . On the top of the strip S and over the eyes R and R' passes a leather strip, T , to which the buttons 45 are to be secured.
- The operation is as follows: The operator using the machine fills the several channels F' of the button-receptacle F' with buttons W , provided with staples W' , as shown in Fig. 6.
- 50 The buttons are placed in the channels so that their eyes pass out between the opening formed by the flanges F^2 , and the cross-arm W^2 of the staple W' rests on the outer side of the said flanges F^2 . The points of the staple W' extend 55 outward and horizontally, as is plainly shown in Figs. 1 and 3. In order to fill each channel F' with buttons it is necessary that the operator should move the disk I with its opening over the corresponding upper end of the 60 channel F' , said disk I serving as a cover to the several channels F' after they are filled with buttons, as described. When the buttons are in place, the operator adjusts the receptacle F so that the lower end of one of the 65 filled channels F' registers with the upper end of the chute or guideway J , and the buttons
- are permitted to pass into the said guideway J in the same manner as they are held in the said channels F' . The spring K prevents the buttons from moving out of the guideway J . 70 The leather on which the buttons are fastened is passed over the anvil E , on top of which rests the leather strip S , adapted to be secured to the inside of the leather, so as to form a very strong hold for the staples W . This 75 leather strip S , however, may be dispensed with. The operator now moves the lowermost button forward under the spring K into the retainer N , as plainly shown in Fig. 8, the arm P^5 of the spring P preventing the button 80 from passing out through the open end of the said retainer N . The button W' now assumes the position shown in Fig. 8, so that the staple W' hangs downward, and when the operator now presses the arms B and B' together the arm 85 B^3 moves the button-holder D downward, so that the points of the staple W' pass into the leather T , and the strip S into the grooves E' and E^2 , which cause the ends of the staple to clinch onto the under side of the leather T or the strip S . 90 When the button-holder D moves downward, the arm P^5 of the spring P passes into the vertical groove D^6 to drop at the upper end of the said groove D^7 into the inclined groove D^7 . When the operator now releases his pressure 95 on the arms B and B' , then the spring C forces the said arms B and B' apart and the button-holder D moves upward. The arm P^5 of the spring P now passes down the inclined groove D^7 into the lower end of the button-holder D 100 and against the front end of the eye and staple W' , already secured to the leather strip D . The rearward motion of the spring-arm P^5 now moves the button and the leather strip to which it is fastened outward, so as to present 105 a new part of the leather strip directly under the button-holder D . The operator now moves another button under the spring K onto the retainer N , and the above-described operation is repeated. When the operator commences 110 to press on the arms B and B' , as before described, the spring O^2 prevents the arm O' from moving downward very rapidly, so that the retainer N is moved upward partly in the slot D^3 of the button-holder D , whereby the 115 arm W^2 of the staple W' is drawn upward tight under the bottom of the button-holder D , so that the arm W^2 rests directly on top of the leather strip T without being pressed into the same; also, the staple will be positively held 120 in position while being driven into the leather, and thus the slipping of the staple and consequent defective fastening of the button is guarded against. Thus sufficient space is 125 formed between the top of the leather strip T and the under side of the button W for conveniently buttoning the button-hole part of the leather on the button W . Thus it will be seen that the buttons can be very rapidly and securely attached to the leather strip.
- If it is desired to operate the machine by a treadle, I place it on a table, as shown in Fig. 13C

- 10, the arm B' being secured at its rear end by a keeper, U, secured on top of the table U², and the arm B' being secured to a keeper, U', also secured on top of the said table U².
- 5 The other arm, B', is guided freely in a slot in the keeper U and is connected by a link, V', with a treadle, V, located on the floor or on the lower part of the table U². The operation above described for fastening the buttons is 10 similar to that now performed, the only difference being that the arms B and B' are pressed toward each other by the link V' and the treadle V, the spring C always serving to press the two arms B and B' apart again, as 15 above described.
- Having thus described my invention, what I claim as new, and desire to secure by Letters Patent, is—
1. In a button-fastening machine, the combination, with pivoted arms, of an anvil and a button-receptacle supported by one arm and a movable button-holder carried on the other arm and adapted to be moved toward the anvil, substantially as shown and described.
  - 25 2. In a button-fastening machine, the combination, with pivoted arms and a spring for pressing said arms apart, of an anvil and a button-receptacle supported by the fork of one arm and a movable button-holder carried by the other arm and adapted to move toward the anvil, substantially as shown and described.
  3. In a button-fastening machine, the combination, with pivoted arms, of an anvil and a cylindrical button-receptacle supported by the fork of one arm, a movable button-holder carried by the other arm, and a chute or guideway for delivering the buttons from the cylindrical button-receptacle to the said button-holder, substantially as shown and described.
  - 35 4. In a button-fastening machine, the combination, with pivoted arms, of an anvil and a cylindrical button-receptacle supported by the fork of one arm, a movable button-holder carried by the other arm, a chute or guideway for delivering buttons from the cylindrical button-receptacle to the said button-holder, and a spring held in the said chute to prevent the buttons from passing into the button-holder, substantially as shown and described.
  - 45 5. In a button-fastening machine, the combination, with pivoted arms, of a cylindrical button-receptacle provided with upright channels held to turn on one of the said arms, a chute adapted to connect with the lower ends of the said channels, and a button-holder moved by the other arm and adapted to connect with the lower end of the said chute, substantially as shown and described.
  6. In a button-fastening machine, the combination, with pivoted arms, of a cylindrical button-receptacle provided with upright channels held to turn on one of the said arms, a chute adapted to connect with the lower ends of the said channels, and a button-holder moved by the other arm and adapted to connect with the lower end of the said chute, and a spring held in the said chute to prevent the buttons from passing out of the lower end of the same, substantially as shown and described.
  7. In a button-fastening machine, the combination, with pivoted arms, of a cylindrical button-receptacle provided with upright channels and held to turn on one of the said arms, and a movable disk held on the top of the said cylindrical receptacle to close the upper ends of said channels, substantially as shown and described.
  - 70 8. In a button-fastening machine, the combination, with pivoted arms, of a cylindrical button-receptacle provided with upright channels and held to turn on one of the said arms, a movable disk held on the top of the said cylindrical receptacle to close the upper ends of the said channels, and a disk held on the said arm and supporting the lower end of the said cylindrical receptacle, substantially as shown and described.
  - 85 9. In a button-fastening machine, the combination, with pivoted arms, of a cylindrical button-receptacle provided with upright channels and held to turn on one of the said arms, a movable disk held on the top of the said cylindrical receptacle to close the upper ends of the said channels, a disk held on the said arm and supporting the lower end of the said cylindrical receptacle, and a chute extending from the said fixed disk and provided with a spring, being also adapted to register with the said channels, substantially as shown and described.
  - 90 10. In a button-fastening machine, the combination, with pivoted arms, of a button-holder held on one of the said arms and held to slide vertically in guideways in the other arm, and a spring secured on the guideways and adapted to pass over the lower end of the said button-holder, substantially as shown and described.
  - 105 11. In a button-fastening machine, the combination, with pivoted arms, of a button-holder held on one of the said arms and held to slide vertically in guideways on the other arm, a spring secured on the guideways and adapted to pass over the lower end of the said button-holder, and an anvil secured to the arm opposite the button-holder, substantially as shown and described.
  - 110 12. In a button-fastening machine, the combination, with a button-holder having a sliding movement and provided on its front with a vertical and an inclined groove, of which the latter is deeper than the vertical groove, of a spring fastened by one end and formed into a coil which extends into a rod provided with a pointed arm passing under the lower end of the button-holder and adapted to engage the said groove, substantially as shown and described.
  - 120 13. In a button-fastening machine, the combination, with an arm, of an anvil having transverse grooves and supported on the said arm, a spring having a slot and fastened on the said arm, and eyes secured on the outer ends of the

said spring at each end of the said anvil, substantially as shown and described.

14. In a button-fastening machine, the combination, with a button-holder having a vertical sliding motion and provided with a transverse slot, of a button-retainer held in the said slot of the button-holder, a rod connected with

the said retainer and mounted to slide vertically, and a spring pressing against the said rod, substantially as shown and described.

AUGUST SCHILLMÖLLER.
